UNITED STATES PATENT OFFICE

1,992,812

WORK ROTATING APPARATUS

Verni J. Chapman, Schenectady, N. Y., assignor
to General Electric Company, a corporation of
New York

Application July 1, 1933, Serial No. 678,646

8 Claims. (Cl. 214—1)

My invention relates to work rotating apparatus particularly adapted for rotating pipe sections when making the circular seams by which these sections are joined to one another.

The present day practice for field welding sections of pipe together is to place several sections end to end on pipe supports or rollers which are commonly called "dolllies", tack weld the joints between these sections and then have one man slowly rotate this assembly while another man makes the circular welds by which the sections are joined together. This enables the welds to be made in the down direction. It has certain objections however, the principal one of which is that it is not always possible to obtain complete harmony and synchronism between the two operators.

It is an object of my invention to provide apparatus for automatically rotating at a substantially uniform rate of speed work parts such as a plurality of lengths of pipe that have been joined to one another at their ends by tack welds.

Further objects of my invention will become apparent from a consideration of the following description of the embodiments illustrated in the attached drawing, Figs. 1 and 2 of which illustrate a side view partly in section and a plan view of one embodiment thereof, and Fig. 3 of which shows another embodiment thereof.

In Figs. 1 and 2 the apparatus for rotating the work is supported on a truck or carriage 10 located to one side of the work which, in this instance, comprises a plurality of pipe sections 11, 12 and 13. The ends of these pipe sections are supported on dolllies 14 or other suitable means for rotation about their longitudinal axes. The ends of each section are joined to the ends of adjacent sections by tack welds 15, so that the several sections may be rotated in unison.

The rotating apparatus comprises a reel 16 supported on and attached to a shaft 17 which is mounted in pedestals 18 resting upon the platform of the carriage 10. The reel 16 is rotated by an electric motor 19 through a transmission comprising reduction gearing 20, a chain drive 21 and the shaft 17 upon which the reel is located. The reel 16 is connected to the work by a rope 22 part of which is wound about the reel 16 and part of which is wound about the work. It may be desirable to attach the free end 23 of the rope to the surface of the work by a clamp 23' in order to hold the rope in driving engagement with the periphery thereof. The clamp illustrated comprises a strip of metal one end of which is tack welded to the surface of the pipe.

It will be noted that the part of the rope wound about the work is sufficient to impart thereto at least one complete revolution when it is pulled from the work by being wound about the reel 16 upon the rotation of this reel through the agency of its driving motor 19. A strut 24, one end of which is attached to the carriage 10 and the other end of which is adapted to engage the work directly or indirectly through the turns of rope 22, as illustrated, is provided for transmitting the reaction of the reeling mechanism directly to the work. This strut comprises members 25 and 26 connected by a turn buckle by means of which the length of the strut may be adjusted. The end 27 of member 25 is supported on the shaft 17 upon which reel 16 is also located and is forked to accommodate the location of the reel intermediate its branches. The member 26 terminates in a yoke 28, the ends of which are provided with rollers 29 which are adapted to engage the work directly or indirectly through the rope 22 as illustrated in the drawing.

With the parts arranged as illustrated in the drawing the operation of motor 19 rotates the reel 16 in a direction to pull rope 22 from pipe 12 about which it is wrapped, and in so doing imparts a rotary motion to this pipe and to the pipes 11 and 13 connected thereto by tack welds 15. The strut 24 located between the work and the pulling means supported on the carriage 10 takes care of the reaction of the pull of the rope and the reeling in of the rope 22 rotates the pipe sections at a uniform rate of speed depending upon the speed of operation of the motor 19 which is adjusted to accommodate the speed of welding. As the pipe sections are rotated the circular seams between their end portions are progressively presented to welders who are thus enabled to make the welds between the parts under the most advantageous and favorable conditions.

In Fig. 3 of the drawing I have illustrated a modification of my invention in which a chain drive is employed for rotating the work. In the arrangement there illustrated a split sprocket ring 30 is applied to the pipe 31 and connected by a chain 32 to a driving sprocket 33. The driving sprocket is supported on a shaft 34 mounted in pedestals 35 which are suitably supported on a carriage or like means as illustrated in Figs. 1 and 2. The parts of the sprocket ring 30 are connected by a link 36 by means of which they are held in firm engagement with the work 31. A rubber strip 37 or a strip of similar material may be interposed between the sprocket ring and the work in order to secure a positive driving.

engagement between these parts. The sprocket ring illustrated is provided with a track on each side of the projections thereof upon which rest grooved rollers 38 supported in the ends of yoke 39 forming the work engaging end or shoe of an adjustable strut 40 having a construction similar to that of the strut 24 described above in connection with Figs. 1 and 2. As in Figs. 1 and 2 the shaft 34 is connected to a suitable motor by means of which an adjustable and uniform rotation may be imparted thereto. The rotation of shaft 34 rotates the driving sprocket 33 which transmits rotation to the sprocket 30 on the work part 31 through the agency of chain 32. The strut 40, one end of which is attached to the supporting means for driving sprocket 33 and the other end of which engages the sprocket ring, properly spaces the parts and transmits the reaction of the pull of the chain directly to the work.

Instead of the rope and chain drive illustrated and described above, other flexible means adapted to make a driving engagement with the periphery of the work may be employed. Furthermore, instead of using a turn buckle to extend the work engaging portion of the strut into engagement with the work, other means may be employed such as a cylinder and fluid operated piston arrangement. It is also to be understood that other pulling means than the reel and sprocket illustrated and described above may be used without departing from my invention.

Apparatus in accordance with my invention is adapted not only for rotating bodies about a horizontal axis, but may also be employed for rotating vertically disposed objects such as barrels. The apparatus illustrated and described in Figs. 1 and 2, for example, may be adapted for this purpose simply by providing a turn-table upon which to support the barrel and by twisting the member 26 of the strut 24 through 90° in order to accommodate the new location of the work part relative thereto.

It is preferable to arrange the parts of apparatus embodying my invention so that the strut engages the work directly at that portion thereof to which the flexible means is applied. It is not necessary, however, that the strut engage the flexible means located about the work as illustrated in Figs. 1 and 2 although in most instances this arrangement will be preferred since it holds the flexible means firmly in driving engagement with the work and prevents slippage. The work engaging shoe of the strut may straddle the flexible means as in the arrangement of Fig. 3, or it may engage the work to one side of the flexible element located thereabout.

In the arrangements illustrated in the drawing the apparatus has been supported on a movable truck or carriage. This truck may also be used for supporting the arc welding generator and leads, or the gas generator, tanks and hose employed by the welding operators in making the joint. It is, of course, obvious that the motor means need not be an electric motor, as illustrated and described above since other means may be employed for this purpose.

Modifications other than those described and referred to above will occur to those skilled in the art, and it is to be understood, therefore, that my invention is not limited to these embodiments which have been used solely for the purpose of disclosing my invention. I seek, therefore, to cover in the appended claims all those modifica-

tions which fall within the true spirit and scope of my invention.

What I claim as new and desire to secure by Letters Patent of the United States, is:—

1. Apparatus for rotating work comprising work supporting means, flexible means adapted to make a driving engagement with the periphery of the work, means for pulling said flexible means from the work to which it has been applied, means for transmitting the reaction of said pulling means directly to that portion of the work to which said flexible means is applied and means independent of the work supporting means for supporting said pulling means and said reaction transmitting means. 5

2. Apparatus for rotating work comprising work supporting means, a flexible element adapted to make a driving engagement with the work, means for pulling said flexible element from the work to which it has been applied, a strut between 10 said pulling means and said work and means independent of the work supporting means for supporting said pulling means and said strut, one end of said strut being attached to said pulling means and the other end thereof being provided 15 with a yoke adapted to engage the work. 20

3. Apparatus for rotating work comprising work supporting means, a flexible element adapted to make a driving engagement with the work, means for pulling said flexible element from the 25 work to which it has been applied, a strut attached to said pulling means, means for extending the work engaging end of said strut into engagement with the work and means independent 30 of the work supporting means for supporting 35 said pulling means and said strut.

4. Apparatus for rotating work comprising work supporting means, a flexible element adapted to make a driving engagement with the work, means for pulling said flexible element from the 40 work to which it has been applied, an adjustable strut one end of which is attached to said pulling means and the other end of which is provided with a shoe adapted to engage the work and means independent of the work supporting means 45 for supporting said pulling means and said strut.

5. Apparatus for rotating work supported independently thereof comprising a sprocket ring, having a track adjacent the projections thereon, means for attaching said sprocket to the work, a 50 driving sprocket, a support for said driving sprocket, means for rotating said driving sprocket at a predetermined rate of speed, a chain extending between said sprockets, and a strut one end 55 of which is attached to said support and the other end of which is provided with a shoe engaging the track on said sprocket ring.

6. Apparatus for rotating pipes supported independently thereof comprising a sprocket ring, means for attaching said sprocket ring to the 60 surface of a pipe, a driving sprocket, means for rotating said driving sprocket, a support for said driving sprocket, a chain extending about said sprockets, and a strut one end of which is attached to the said support and the other end of 65 which is adapted to engage said sprocket ring.

7. Apparatus for rotating work comprising work supporting means, a flexible element adapted to make a driving engagement with the work, a reel about which a part of said flexible element is 70 wrapped, means for rotating said reel at a substantially uniform rate of speed, means independent of the work supporting means for supporting said reel, and a strut attached to said supporting means between said reel and the work 75

with which the free end of said strut is adapted to engage.

8. Apparatus for rotating work comprising work supporting means, motor means, means for supporting said motor means independently of said work supporting means, means extending from said motor means into driving engagement

with work supported on said work supporting means, and means extending from said motor supporting means and reacting against the work for holding said motor means and the work in adjusted relationship against the reaction of said last-mentioned means. 5

VERNI J. CHAPMAN.

CERTIFICATE OF CORRECTION.

Patent No. 1,992,812.

February 26, 1935.

VERNI J. CHAPMAN.

It is hereby certified that error appears in the printed specification of the above numbered patent requiring correction as follows: Page 2, first column, line 21, for "drive" read drives; and line 62, for "hose" read hoses; same page, second column, lines 21, 22 and 23, claim 2, strike out the words "and means independent of the work supporting means for supporting said pulling means and said strut" and insert the same after "work" in line 26, of said claim; and that the said Letters Patent should be read with these corrections therein that the same may conform to the record of the case in the Patent Office.

Signed and sealed this 16th day of April, A. D. 1935.
